US00D768370S

(12) **United States Design Patent** (10) **Patent No.:** **US D768,370 S**
Kanji et al. (45) **Date of Patent:** **** Oct. 11, 2016**

(54) **SHOE CREASE PREVENTION INSERT**

(71) Applicants: **Alim Kanji**, Toronto (CA); **Aly Khan Ratansi**, Toronto (CA); **Samir Kanji**, Toronto (CA)

(72) Inventors: **Alim Kanji**, Toronto (CA); **Aly Khan Ratansi**, Toronto (CA); **Samir Kanji**, Toronto (CA)

(**) Term: **14 Years**

(21) Appl. No.: **29/504,468**

(22) Filed: **Oct. 6, 2014**

(51) LOC (10) Cl. **02-04**

(52) U.S. Cl.

USPC **D2/961**

(57) **CLAIM**

The ornamental design for a shoe crease prevention insert, as shown and described.

DESCRIPTION

FIG. 1 is a front perspective view of a shoe crease prevention insert, showing our new design;

FIG. 2 is a bottom view thereof;

FIG. 3 is a top view thereof;

FIG. 4 is a right side view thereof;

FIG. 5 is a left side elevation view thereof;

FIG. 6 is a rear side elevation view thereof; and,

FIG. 7 is a front side elevation view thereof.

1 Claim, 6 Drawing Sheets
